COMBINED NAPKIN HOLDER AND CONDIMENT CADDY

Hyman Abrams, Paramus, N.J.
(P.O. Box 27, North Hackensack Station, River Edge,
N.J. 07661)

Filed Dec. 13, 1974, Ser. No. 532,592

Term of patent 14 years

Int. Cl. D7—06

U.S. Cl. D7—72

FIG. 1

FIG. 2

FIG. 3

FIG. 4

FIG. 5

FIG. 1 is a front perspective view of a combined napkin holder and condiment caddy showing my new design;

FIG. 2 is a top plan view thereof;

FIG. 3 is a front elevational view thereof;

FIG. 4 is a side view thereof; and

FIG. 5 is a bottom plan view thereof.

I claim:

The ornamental design for a combined napkin holder and condiment caddy, as shown.
